FABRIC COVERED BUCKLE

Stephen Lerma, Flushing, N. Y.

Application February 21, 1948, Serial No. 10,022

1 Claim. (Cl. 24—163)

1

This invention relates to washable fabric covered buckles which are substantially flat or solidly filled with fabric as distinguished from hollow buckles, so as to prevent moisture from entering within the buckle and thereby eliminate the discoloring of the fabric which is caused when a hollow fabric covered buckle is subjected to washing operations.

In the production of fabric covered buckles, it has been customary to provide two body members having flanges which are assembled in nested relation, the flanges being of considerable depth and thereby causing a space to be formed between the body members of the buckle. In practice it is found that moisture remains in the buckle when the belt and attached buckle are washed or dry cleaned. The cleaning liquid finds its way into the hollow spaces in the buckle and then seeps along the fabric to the outside thereof and discolors the fabric covering of the buckle and of the garment.

An object of this invention is to provide a fabric covered buckle structure which will prevent the discoloration of the fabric covering when the buckle is washed or dry cleaned.

Another object of this invention is to provide a washable fabric covered rectangular buckle comprising a frame body member which is substantially flat or solidly filled with fabric, having two apertures separated and defined by an integral cross-bar and having substantially right-angled outer corner portions removed, triangular portions of the inner corner portions of the apertures in the frame body member being removed, the frame body member being thin and formable, the opposed edge portions of the frame body member being inturned toward each other to provide means whereby a fabric stretched over the outer face of the buckle will have its edge portions disposed inside and clamped by the inturned edge portions of the frame body member, and to provide a thick and flat reinforcing plate member for the frame body member, the plate having a single central aperture coextensive with the two frame body apertures, the plate member having its outer edges in entirety circumscribed by the inturned edge portions of the frame body member, the frame body member and the plate member being in adjoining parallel relation to prevent moisture from entering therebetween.

Another object of this invention is to provide a washable buckle covered on both faces with fabric and arranged to fully cover the faces of the frame body member and the reinforcing plate member in entirety so as to prevent any hollow spaces or pockets from being formed inside the buckle.

With the above and other objects in view, the invention will be hereinafter more particularly described, and the combination and arrangement of parts will be shown in the accompanying drawings and pointed out in the claims which form part of this specification.

2

Reference will now be had to the drawings, wherein like numerals of reference designate corresponding parts throughout the several views, in which:

- 5 Figure 1 is a front view of the assembled buckle.
 Figure 2 is a rear view of the buckle shown in Figure 1.
 Figure 3 is a plan view of a developed blank of a frame body member forming part of the buckle.
 10 Figure 4 is a plan view of a reinforcing plate member for the frame body member.
 Figure 5 is a plan view of a section of fabric which is stretched over the outer faces of the buckle.
 15 Figure 6 is an enlarged cross-sectional view of a fragmentary portion of the buckle, the section being taken on line 6—6 in Figure 1.
 Figure 7 is a plan view of a developed blank of a modified frame body member.
 20 Figure 8 is a front view and Figure 9 is a rear view of the modified buckle.
 Figure 10 is an enlarged cross-sectional view of a fragmentary portion of the modified buckle, the section being taken as on line 10—10 in Figure 8.
 25 Figure 11 is a cross-sectional view, similar to Figure 6, but on a very greatly enlarged scale to clearly show the extent of the cloth covering.
 In the illustrated embodiment of the invention, 30 Figure 1 shows a front view and Figure 2 shows a rear view of a fabric covered buckle 10 embodying the invention.
 Figure 3 is a plan view of a frame body member 11 which is made of thin and formable soft sheet metal. The frame body member 11 has substantially right-angled outer corner portions 12 removed to form outer rectangular bendable edge portions 13, 13' which may be inturned. The frame body member 11 has two apertures 14 separated and defined by an integral cross-bar 15. Triangular portions 16 of two inner corners defining each of the apertures 14 are removed to form inner rectangular bendable edge portions 17, 17' which may be inturned to face toward the inturned edge portions 13, 13' for clamping a fabric section 18 in stretched condition over each outer face of the buckle 10.
 Figure 4 is a plan view of the reinforcing plate member 19 which is made of metal having a degree of rigidity and considerably thicker than the frame body member 11. The plate member 19 has a central opening 20 and two solid rectangular portions 21 connected by side bars 22 and without any cross-bar.
 45 50 55 In assembled relation, in the buckle 10, the plate member 19 has its outer edges in entirety circumscribed by the inturned edge portions of the frame body member 11.
 Buckles used for the ornamentation of garments may be of large size and the cross-bar may have a length of about two inches for use with wide belts. The elongated cross-bar 15 must be

reinforced to withstand the strains brought to bear on it due to the tightening of the belt, and for this purpose the cross-bar is given a rounded shape 15', that is, of substantially circular cross-section, to form a rigid reinforcement for the cross-bar.

It is desirable that the tongue 24 of the buckle 10 should be centrally disposed on the body portion of the assembled buckle, and while it is contemplated to make the width of the belt of the same width as the cross-bar, there is provided an offset bearing or seat on the cross-bar for centralizing the tongue 24.

As shown in Figure 6, it will be seen that the rear face 25 of the buckle 10 is circumscribed by a flange 26 while the front face 27 lies in a single plane. The thickness of the buckle around the outer edge portions is considerably thicker than the body of the buckle. At the central openings 14 there is a ridge 28 which circumscribes both openings and which faces the rear face 25.

As shown in Figure 5, the fabric section 18 has dot-and-dash lines showing sideways foldable inner edge portions 29, 29' and outer edge portions 30, 30' which are clamped between the frame body member 11 and the reinforcing plate 19. At the central portion of the fabric section 18 is a rectangular aperture 23 which defines the inner foldable edge portions 29, 29' which are also clamped between the frame body member 11 and the reinforcing plate 19.

In assembled relation, a fabric section 18 is used for covering the normally exposed surface of the buckle. An additional fabric section 18' is used for covering the rear surface of the buckle 10.

It is to be noted that the section 18' is somewhat longer than the section 18, the object being to make the sections 18 and 18' long enough to cover all the inner spaces between the frame body member 11 and the plate 19. The outer corners of the fabric sections 18, 18' are considerably rounded to avoid excess material at the corners of the assembled buckle.

In types of washable and moisture proof buckles of the character herein described, it is desirable to make buckles which do not have in-turned side edges at the central apertures. A modified washable buckle of this type is shown in Figures 7 to 10 inclusive and comprises a frame body member 31 which is made of thin and formable soft sheet metal.

As shown in assembled relation, it will be noted that the bendable edge portions of flanges 33, 33' are folded to lie flat over the outer edge portions of the reinforcing plate 19.

The frame body member 31 has substantially right-angular outer corner portions 32 removed to form outer rectangular bendable edge portions 33, 33' which may be in-turned. The frame body member 31 has two apertures 34 separated and defined by an integral cross-bar 35. It is to be noted that the upright side walls 36 defining the apertures 34 do not have in-turned side edges.

Figure 8 shows a front view and Figure 9 shows a rear view of a modified buckle 40. It is to be noted that the buckle 40 comprises one of the reinforcing plate members 19 shown in Figure 4, and that in assembled relation, shown in Figure 10, the rear face 41 of the buckle 40 is circumscribed by a flange 42 while the front face 43 lies in a single plane.

Similar to that shown in Figure 6, the thickness of the buckle around the outer edge portions is considerably thicker than the body of the

buckle. At the central openings 34 the absence of the ridge 28 shown in Figure 6, is evident. The plate 19 is shown without any covering fabric.

It is to be noted that the fabric extending beyond the dot-and-dash fold lines must be sufficient to cover the bendable edge portions 13, 13' twice and then extend sufficiently to cover about one-half the distance between the parallel dot-and-dash line, as shown in Figure 5.

It is also to be noted that the reinforcing plate member 19 may be made of plastic material, which will not rust when without fabric covering and exposed. The plastic material may be of a color which will harmonize with the color of the fabric covering material.

In accordance with the patent statutes I have described and illustrated the preferred embodiments of my invention, but it will be understood that various changes and modifications can be made therein without departing from the spirit of the invention as defined by the appended claim.

I claim:

In a fabric covered buckle comprising a frame body member having two apertures separated and defined by an integral cross-bar, said frame body member having flanges with arcuate ends shaped to substantially contact each other, triangular portions of inner corners defining each of said apertures being removed to cause the opposed edge portions to substantially contact each other when inturned, a centrally apertured plate having two solid rectangular portions connected by side bars and being coextensive with all the effective boundary edges of said frame body member and substantially filling the space between said inturned edges, said plate member being disposed in nested parallel relation with said frame body member and within said inturned edge portions of said frame body member, said flat plate causing the bent flanges to lie flat, a section of fabric stretched over the outer face of said buckle and having its free edge portions disposed in nested relation within said inner and outer inturned edge portions and extending between said frame body member and said plate member and fully covering all the surfaces of said body member, and a further section of fabric stretched over the outer face of said plate member and extending rearwardly of said plate member and fully covering all the surfaces of said plate member, the covering fabric on said frame body member and the covering fabric on said plate member being in contacting relation, said buckle having two layers of fabric between said frame body member and said plate member for preventing moisture from entering between said members, said double fabric layers forming a buckle solidly packed in cross-section thereby preventing the collection of water inside said buckle.

STEPHEN LERMA.
